UNITED STATES PATENT OFFICE.

WILLIAM H. WALTERS, OF ALTOONA, PENNSYLVANIA.

THROTTLE-VALVE.

1,274,112.

Specification of Letters Patent.

Patented July 30, 1918.

Application filed January 17, 1918. Serial No. 212,306.

To all whom it may concern:

Be it known that I, WILLIAM H. WALTERS, a citizen of the United States, residing at Altoona, in the county of Blair and State of Pennsylvania, have invented certain new and useful Improvements in Throttle-Valves, of which the following is a specification.

This invention relates to locomotive boilers, and has particular reference to locomotive throttle valves, which are usually positioned in or beneath the locomotive dome.

The primary object of this invention is to provide a locomotive throttle valve with a balancing chamber in connection with a pilot or relief valve having a pendent stem having positioned thereon a valve designed to control the steam pressure within the valve balancing chamber.

Another object of this invention is to provide a system of cored passages through which steam passes to the balancing chamber after the pilot valve is opened and through which the steam escapes from the balancing chamber.

With these and many other objects in view which will be more readily apparent as the nature of the invention is better understood the same consists in the novel construction, combination and arrangement of parts as will be hereinafter more fully illustrated pointed out and claimed.

It will be quite readily understood by those skilled in the art to which this invention belongs that the same is susceptible to various changes and modifications without departing from the spirit or scope of the invention, but a preferred and practical embodiment of the same is illustrated in the accompanying drawings in which—

Figure 1 is a cross sectional view of a throttle valve having the present invention applied thereto, as well as showing a sectional view of the throttle chamber together with a portion of the throttle valve operating mechanism.

Fig. 2 is an end elevation of the parts shown in Fig. 1, having the throttle valve shown in dotted lines.

Fig. 3 is a view showing a modified form of the balancing chamber regulating valve.

Similar reference numerals refer to similar parts throughout the several figures of the drawings.

In carrying out this invention no change

is contemplated in the locomotive boiler, dome or throttle chamber which is designated in its entirety by the numeral 10, and which consists primarily of an L shaped casting, provided with an opening 11, through which the steam enters from the dome of the boiler. The chamber 10 is further provided with an opening 12, which is positioned at right angles to the opening 11, and through which steam passes upon entering the dry pipe, which is connected through suitable steam pipes to the steam chest in which is positioned the main valve that controls the distribution of steam in the locomotive cylinder.

Within the throttle chamber C, there is provided an inwardly projecting ledge or flange 13, which is formed integral with the casting, having machined thereon a ledge or shoulder 14, against which there is adapted to rest a collar 15, made integral with an angular valve seat 16. This valve seat 16 is preferably made of a different metal from that in the valve chamber, the metals having a different coefficient of expansion so as to more readily accommodate itself to the varying temperature conditions of the boiler as well as to provide a valve seat that will not rust thus insuring a perfect seat for the coacting valve 17 which is designed to control the supply of steam from the locomotive boiler to the dry pipe.

The valve 17 is preferably made of the usual approved construction, having guide wings 18, which are adapted to engage the inside 19 of the annular valve seat ring 20, thereby insuring a perpendicular lift of the valve.

The valve 17 is further provided with a central opening 21, around which is formed a valve seat 22, adapted to coact with a valve 23, formed integrally with a stem 24, which carries a piston valve 25, adapted to travel in a vertical plane in the piston chamber 26. The chamber 26 is provided with a steam port 27 through which steam may escape from a valve balancing chamber 28. On either side of the piston valve chamber there is provided steam ports 29, through which steam enters from the boiler to the balancing chamber and through which steam must pass to the chamber release port 27. It will be readily noticed that the valve 17 is provided with a pendent bell shaped portion 30 having a central opening 31, and a

collar 32, the lower face of which forms a shoulder 33 against which impinges a shoulder 34 positioned upon the balance piston 35, which is designed to travel in a vertical plane in the balancing chamber 28.

5 The operation of this valve may be described as follows:—

An outward pull on the throttle valve operating rod 36, by virtue of the introduction 10 of the bell crank 37 results in an upward movement of the link element 38, which motion is transferred to the yoke 39 positioned above the valve 17. The yoke 39 is provided with vertical guiding means in the 15 form of a slot 40 which is shown cast integral with the periphery of the top portion 41 of the valve chamber 10. Interposed between the yoke 39 and the valve 23 there is a link 42, preferably bifurcated at 20 the top end, and having a pin connection 43 with the yoke 39. The lower end 44 of the link 42 is adapted to have a pin connection 45 with the bifurcated extension 46 of the valve 23 as shown in Fig. 1 of the 25 drawings.

Obviously an upward movement of the link will impart a like movement to the 30 valve 23 permitting the same to leave the valve seat 22 allowing steam from the locomotive boiler dome to pass into the cavity 47 which surrounds the pendent stem 24 which carries a piston valve 25, positioned so as to close the port 27 when the valve 23 is opened, thus directing the steam through 35 the ports 29 to the balancing chamber 28 raising the valve 35 together with the valve 17 at which time steam readily flows from the locomotive boiler dome through the valve opening 48 to the opening 49, from 40 whence it flows through the dry pipe to the steam chest and thence to the locomotive cylinders. The balancing of the valve 17 takes place almost instantaneously with the opening of the valve 23 and since the valve 45 becomes balanced with the opening of the valve 23 it obviously becomes easy for the engineman to control the throttle opening at will. Upon closing the throttle valve 17 the engineman first closes the pilot valve 23 50 which at once opens port 27 leaving the steam escape from the balancing chamber 28, the valve 17 is then easily closed.

Referring now to Fig. 3 it will be observed that the piston valve 25 is replaced 55 by a cone shaped valve 50, while the valve seat 51 is an integral part of the bell shaped pendent portion 30, preferably made integral with the valve 17.

When the valve 23 is lifted from its seat 60 22 the cone shaped valve 50 approaches its seat 51. The steam then passes from the boiler dome into the cavity 47 from thence it passes through ports 29 to the balancing chamber 28. In this construction the steam 65 from the balancing chamber escapes through

the opening 52. While no claim will be laid upon this particular shape of cone valve it should be readily understood that the method of arranging the ports 29 in the bell shaped pendent portion of the valve 17 70 is a part of the present invention and the same will be set forth in the appended claims.

From the above description it is believed 75 that the many advantages of the herein described throttle valve mechanism will be readily apparent to those skilled in the art to which this invention belongs, and what I claim and desire to be covered by Letters Patent is—

1. In a throttle valve, in combination, a throttle chamber open at its upper end and having its lower end connected to the dry pipe, a removable valve seat positioned within the throttle chamber adjacent the upper 85 end opening, a valve adapted to coöperate with the seat, a pendent bell shaped portion for the valve, a central opening in the valve and a piston adapted to operate in the opening and have a vertical movement therein. 90

2. In a throttle valve, in combination, a throttle chamber having an opening in its upper end and having its lower end secured to the dry pipe, a valve seat, a ledge cast 95 integral with the valve chamber for holding the valve seat, a vertically movable valve adapted to coact with the valve seat, a central opening in the valve, a balancing chamber, a piston adapted to have a vertical movement in the chamber, and a valve seat 100 formed integral with the said movable throttle valve, a valve coacting with the valve seat such as to control the flow of steam to the balancing chamber, a stem held pendent from the valve carrying means for 105 controlling the egress of steam from the balancing chamber.

3. In combination with a throttle valve, a chamber for the valve, an orifice in the top of the chamber for admitting steam to the throttle valve, a bell shaped pendent body on the said valve, a collar on the bell portion, a balancing chamber, a piston adapted to coact with the said throttle valve and have a vertical movement within the 110 chamber, a central opening in the valve, a piston valve, a port in the pendent bell shaped portion adapted to be open and closed by the piston valve and a plurality 115 of steam ports within the bell shaped portion of the valve through which steam may pass to and from the balancing chamber. 120

4. In combination with a throttle valve, a chamber for the valve, means for admitting steam to the valve, a valve seat, a valve coacting with the seat, pendent wings on the valve, a balancing chamber, a piston portion of the valve having vertical movement within the chamber, a pilot valve, a seat in the said throttle valve coacting with 130

the pilot valve, a pendent stem carried by the valve, a piston on the stem, an exit steam port adapted to be covered and uncovered by the piston valve when balancing the 5 valve, steam ports in the pendent bell of the valve for conducting steam around the walls of the piston valve cylinder to and from the balancing chamber, and means for opening

and closing the pilot valve and the throttle valve.

10

In testimony whereof I affix my signature in the presence of two witnesses.

WILLIAM H. WALTERS.
